Edward T. Beach

UNITED STATES PATENT OFFICE.

MATTHEWS E. DAVIS, OF NEW YORK, N. Y.

SHIP-PROPELLER.

1,216,549.

Specification of Letters Patent. Patented Feb. 20, 1917.

Application filed June 16, 1916. Serial No. 103,916.

To all whom it may concern:

Be it known that I, MATTHEWS E. DAVIS, a citizen of the United States, residing at New York city, in the county of New York and State of New York, have invented certain new and useful Improvements in Ship-Propellers, of which the following is a specification.

This invention relates to improvements in steel or cast iron ship propellers and the protection of steel or iron hulls from electrolysis when provided with my improved propellers.

Steel or cast iron propellers are more desirable than bronze propellers or propellers made of special metals because they are cheaper and also because their blades are not so apt to be distorted by collisions with obstacles that commonly bend bronze and special metal blades. On the other hand, steel and cast iron propellers become so pitted in the blade tip portions, especially in salt water, that new propellers are required about every two years and sometimes 25 oftener. A theory of the cause of the pitting action accepted by some authorities is that oxygen is released from the air bubbles which form on the backing side of the propeller blades just aft of the forward edge 30 toward the tips, and attacks the steel or cast iron. To avoid this destructive action, steel and cast iron propellers have been painted or covered with cement, but these methods do not give a satisfactory protection and 35 resort has been had to detachably mounted blade tips permitting replacement of the eaten out or pitted tips, the zone of deterioration usually extending one-third of the length of the blade from the tips and 40 being just back of the entering edge on the back of the blade. The best approved means of avoiding the damage to steel or cast iron propellers is to give up their use and use the more expensive bronze propellers even 45 though the blades of bronze propellers are less stiff and more subject to deformation than steel or cast iron propellers. While I have referred to propellers of special metal, I am not aware that any satisfactory substitute for steel, cast iron and bronze has 50 been found for approved use in the manufacture of ship's propellers, especially for salt waters.

My idea of an effective way of overcom- 55 ing the expense and annoyance attendant on the use of steel and cast iron propellers is

to coat them with copper or other metal which is highly resistant to the action of oxygen in salt water, or at any rate is highly resistant to the pitting action mentioned. But inasmuch as propellers of the class which is particularly within the object of my improvement are almost invariably used in steel hulls, the copper or resultantly equivalent metal coating, if such metal comprises copper, leads to a practical difficulty of the utmost importance, so that although my metallically coated steel or cast iron propellers are of themselves highly desirable from the viewpoints of low cost, 60 stiffness and approximate non-deformability, yet they are considered of and by themselves, and simply as non-pitting metallically coated propellers, antagonistic in effect to steel or iron hulls, and would involve 65 ultimate destructive damage thereto, because of electrolysis, if it were not that by my invention means are provided for efficiently nullifying the constantly existing electrolysis so far as destructive action on 70 the steel or iron hull is concerned. My problem therefore involves a reconciliation of antagonisms, and this I accomplished by the means described below. The electrolysis results from the proximity of the propeller 75 when coated with copper or with a special metal containing copper, and of the steel or iron hull in water, especially salt water, the copper, steel or iron and salt water setting up a strong electrolytic or galvanic current 80 that is very rapidly destructive of a steel or iron hull. Moreover electrolysis or some similar destructive process is more and more encountered in the present times because of the use of wireless telegraphy and the 85 grounding of electric current leads in harbors, and the question of the protection of steel or iron hulls from such destructive agencies is one of large importance. Just how far, if at all, the electrolytic or gal- 90 vanic forces are increased by other currents alluded to, nobody knows. At any rate, if copper or a copper-containing metal is to be used to coat steel and cast iron propellers as is highly desirable for economy of manu- 95 facture and durability of propeller blades, then it is essential that the electrolytic or galvanic action referred to be made negligible on steel or iron hulls equipped with so coated propellers.

Efficiency requires that the outward surfaces of the propeller be smooth in order to

slip smoothly in water and minimize skin friction, and my improved propellers coated with copper or metal containing copper have a smooth skin or outward surface which is durable. Considered by itself, my new steel or cast iron copper-coated propeller is stiffer and cheaper than bronze propellers, better than paint or cement covered steel or cast iron propellers because it will not crack or peel off, adds strength to the steel or cast iron blades which a coating of paint does not do, and slips better in water. Moreover my copper coating lines the hub bore and keyway and thus protects so much of the steel shaft as is in the hub bore, also protecting the steel key that splines the propeller hub to the shaft. I form my coating by plating or other suitable coating process, of which several are known.

The accompanying drawing forming a part hereof is a vertical central section of one form of a propeller and its mounting in a steel or iron hull, and fully illustrates my invention as embodied in a built-up propeller. The cored-out and thereby chambered steel or iron hub is interiorly and also externally coated, and the demountable steel or iron blades are also wholly coated in the form shown.

In the drawing, 1 is a steel propeller shaft having a stern end taper, 2 a bronze sleeve shrunk in place on the steel shaft, 3 a built-up propeller hub of cast iron or steel forming a core for the coating or incasement of plated metal, 4 the propeller blades of cast iron or steel, 5 the copper or equivalently functioning coating or incasement, 6 an annular recess in the forward end of the hub for reception of the sternward end of the bronze sleeve, 7 a water-excluding gasket at the joint between the opposed ends of said sleeve and hub, 8 the clamp nut which holds the propeller in place on the shaft in co-operation with the key 9. 10 are taps which hold the demountable blades to the hub, and 11 is a lignum vitæ bearing in which the bronze sleeve is mounted, this lignum vitæ bearing insulating the iron or steel hub from the bronze sleeve. 12 is a fair water which may be omitted if preferred, and 13 are zinc plates shown mounted in functional proximity to the propeller. Some of these zinc plates are on the walls of the propeller aperture, and one of them is indicated by dotted lines as applied to the usual hublike portion of the propeller aperture where the propeller shaft passes into such aperture to

hold the propeller in place. The zinc plates 13 function as protectors for the steel or iron hull against electrolytic action which severely attacks the zinc and leaves the hull comparatively safe from electrolysis. These zinc protector-plates are eaten in time and have to be replaced at intervals.

The copper-containing metal is the best kind of metal now known to me for resisting the pitting action. But any other pitting-resisting metal which at the same time will act with another metal in proximity to a propeller insulated from an iron or steel hull for protection of such hull against electrolytic injury, I deem to be an equivalent of my preferred copper-containing metal for all purposes; and it is to be observed that the coating which I have referred to for the propeller is not merely a thin skin, but is a deposit or coating or plating of substantial thickness whereby it adds to the strength of the propeller blades cross-sectionally. It also adds in a certain sense to the strength of the hub, but the hub is not under such strains as are the propeller blades and it is the strengthening of the steel or iron propeller blades by the metallic coating that is important. Obviously the propeller may be a built-up propeller such as herein shown, or a single-piece propeller in which the hub and blades are integral.

What I claim is:

The combination of an iron or steel hull, with a steel propeller shaft having a fixed sleeve insulated from the hull; a propeller keyed to and also clamped endwise in place on the shaft; and a gasket between the opposed walls of the sleeve and propeller hub; the propeller comprising an iron or steel propeller-shaped core and a copper-containing metal coating on its surfaces, and the hull being provided with removable zinc plates adjacent the propeller; the copper-containing metal coating resisting pitting and preventing pitting of the coated propeller core and of the portion of the shaft in the propeller hub bore; and the zinc plates in proximity to the propeller protecting the hull against electrolytic action; and the gasket excluding water from access to the shaft at the joint between the opposed walls of said sleeve and propeller hub; and the said metallic coating increasing the strength of the blades cross-sectionally.

In testimony whereof I have hereunto set my hand this 13th day of June, 1916.

MATTHEWS E. DAVIS.
